Primary Examiner — Eric Goodman*Assistant Examiner* — Clare Ann Gannon(74) *Attorney, Agent, or Firm* — Northern Michigan Patent Law, PLLC(57) **CLAIM**

We claim the ornamental design for a privacy booth, as shown and described.

DESCRIPTION

FIG. 1 is a front perspective view of a privacy booth embodying the new design.

FIG. 2 is a front elevation view of the privacy booth of FIG. 1. FIG. 3 is a right side elevation view of the privacy booth of FIG. 1.

FIG. 4 is a top plan view of the privacy booth of FIG. 1.

FIG. 5 is a left side elevation view of the privacy booth of FIG. 1; and,

FIG. 6 is a rear elevation view of the privacy booth of FIG. 1. The broken lines depict portions of the privacy booth that form no part of the claimed design. The bottom is omitted and forms no part of the claimed design.
